UNITED STATES PATENT OFFICE.

ST. ELMO SANDERS, OF KANSAS CITY, MISSOURI.

SURGICAL-NEEDLE HOLDER.

Application filed February 20, 1928. Serial No. 255,699.

My invention relates to pincers and more particularly to surgical needle holders, the principal objects of the invention being to effectively retain needles of different forms and diameters and release the same from the retaining means, without undue strain on the needle or the device, and with a minimum of effort by the operator.

In accomplishing these and other objects of the invention I have provided improved details of structure, the preferred forms of which are illustrated in the accompanying drawings, wherein:

Fig. 1 is a perspective view of my improved needle holder in open position.

Fig. 2 is an enlarged perspective view of the jaws of a holder embodying my improvements.

Fig. 3 is a perspective view of the holder in closed position.

Fig. 4 is an enlarged fragmentary view partly in section of a holder in open position and a needle on the seat of the lower jaw.

Fig. 5 is a similar view illustrating the device in needle holding position.

Fig. 6 is a plan view similar to that of Fig. 5.

Fig. 7 is a fragmentary plan view of the lower jaw member of the device.

Referring in detail to the drawings:

1 and 2 designate relatively long handled cooperating members of pincers, pliers or forceps, pivotally connected by a pin 3 and having finger loops 4 and 5. One member, illustrated as member 1, is preferably provided with an elongated slot 6 in an enlarged pivotal portion 7 to receive the similarly enlarged but transversely reduced portion 8 of the other member to provide relatively extensive bearing areas to absorb lateral or twisting strains, the structure comprising a box lock. The pivot portions are provided with mating shoulders, such as 9 and 10. Jaw 11 of the member 1, which may be called the lower jaw of the holder, comprises a body portion 12 having a horizontal or flat and relatively broad face 13, and an upstanding nose 14 having a truncated flat-faced tip 15 and a vertical inner wall 16 extending in a straight line transversely of the jaw. The meeting angle of the face 13 and wall 16 preferably comprises a right angular needle seat 17, and the wall and tip face meeting in a common edge 18. The opposite jaw 19, on the member 2, com-

prises an arcuate and narrow body 20 and a rearwardly downwardly tapering nose 21, the lower edge 22 of the nose being receivable in a recess 23 formed in the body portion 12 of the lower jaw. The nose comprises a taper and preferably convexly curved lower portion 24, adapted for progressively closer approach to the needle seat upon pivoting of the members, and being formed on a radius substantially greater than the height of the right angular needle seat.

The relation between the parts of the two jaws is such that the lower portion 24 of the upper nose may move past the nose of the lower jaw and move in a path spaced from the needle seat, while the upper portion 25 of said nose would engage the edge 18 of the lower nose upon operation of the holder, except for stopping of the pivoting movement by the held needle, or other parts of the members.

The lower edge 22 of the upper nose comprises a common edge for the convex face of the lower portion 24 and the concave under face 26 of the jaw whereby the seating and engagement of a needle in the holder is facilitated and the provision of an imperforate lower jaw having a relatively shallow recess is permitted. The recess 23 may extend into the needle seat whereby spaced and aligned seat elements designated 27 and 28, Fig. 7, may be produced.

Means for engaging the members 1 and 2 in needle holding position comprise a hook 29 adjacent the finger-engaging loop of one member, and ratchets 30, 31 and 32 on the opposite member. The ratchet teeth have under faces extending substantially at right angles to the plane of the members 1 and 2 and the hook is formed on an acute angle whereby lateral pressure of the fingers holding the loops may release the hook from a ratchet tooth, the relatively long and resilient handles facilitating the engagement and disengagement.

In operating the device, a needle is positioned on the seat of the lower jaw, resting longitudinally against the transverse face of the jaw nose, the straight transverse edge 18 of the lower jaw serving the senses of sight and touch for positioning the needle and assuring the proper fixing thereof. The opposite jaw member is moved into contact with the needle, the lower portion 24 of the upper jaw nose constituting the needle-en-

gaging element. The relation between the cam face and the lower jaw provides that the continuation of the pivoting causes the upper nose to exert its greatest influence downwardly while also exerting end thrust to adjust the needle to its seat. The nose edge may pass the seat and enter the recess of the lower jaw when a small needle is held.

The device is, therefore, adapted for securely holding needles of different diameter and form, and for conveniently and securely grasping the differently formed and sized portions of a needle. The body portion of a needle is slightly bent into the recess under the pressure of the upper nose; and the recess receives the curve of a curved needle whereby spaced seat elements support spaced portions of the needle and danger of breakage upon closing or releasing the jaws is obviated. The means for locking the handles enables the user to release the jaws with slight effort and without appreciable strain on the needle held. The long and resilient handles provide the spring element for enforcing the engagement of the latching members, the ratchets and hook being so placed that the handles must be tensioned to bring the hook and handles into engagement. Attention is called to the fact that pressure upon the handles will not alone disengage the locking means.

What I claim and desire to secure by Letters Patent is:

1. A needle holder including a jaw member having a vertical nose provided with a flat faced tip having a transverse straight edge, and an opposite jaw member having a rearwardly tapering face, the jaws being movable towards intersection of the face by the edge.

2. In a device of the character described, pivotally connected members having mating jaws, the jaw of one member having an upstanding nose provided with a vertical inner wall, the jaw of the other member having a cam-faced nose provided with a transverse lower edge movable when adjacent the wall of the first-named nose and an upper portion engageable with said first named nose upon pivoting of the members.

3. A needle holder including pivoting jaws, one having spaced needle seats, a nose-receiving recess and a fixed upstanding needle retaining nose, and the other having a taper nose movable towards engagement with the needle seat and having a lower edge receivable in said recess.

4. In a needle holder, pivoted upper and lower jaws, the lower jaw having a horizontal face provided with a recess, and a vertical nose provided with a rearwardly facing plane surface parallel with the pivotal axis and meeting the horizontal face in a right angle to provide a needle seat, the upper jaw having a tapering nose provided with a shaped lower portion movable past the nose of the lower jaw and with a shaped upper portion movable towards engagement with the nose of the lower jaw upon pivoting of the jaws.

5. A needle holder comprising pivoted upper and lower jaws, the lower jaw having a horizontal face provided with a recess and a vertical nose having a transverse straight upper edge, the upper jaw having a nose provided with a shaped lower portion spaced from the vertical nose of the lower jaw in closed position and with a shaped upper portion movable in a path intersecting the straight upper edge of the nose of the lower jaw upon pivoting of the jaws.

6. A needle holder comprising pivoted members having relatively elastic handles and jaws provided with longitudinally offset noses, one nose having a cam face provided with a portion movable in a path spaced from the other nose and a portion movable in a path intersecting said other nose, and locking means comprising a ratchet on one member having substantially horizontal faces and a hook on the other member whereby horizontal lateral pressure will release the hook from the ratchet.

7. A needle holder including mating jaws, one having spaced needle seats, a nose receiving recess spacing said seats and an upstanding nose, and the other having a taper nose receivable in said recess.

In testimony whereof I affix my signature.
ST. ELMO SANDERS.
